[57] CLAIM

The ornamented design for a decorative cap for a process transmitter, as shown and described.

DESCRIPTION

FIG. 1 is a front perspective view of a decorative cap for a process transmitter embodying a first form of our new design;

FIG. 2 is a front elevational view thereof;

FIG. 3 is a side elevational view thereof with a transmitter to which it is attached shown in dotted lines;

FIG. 4 is a rear elevational view thereof;

FIG. 5 is a top plan view thereof; the side not shown being a mirror image of the side shown and the bottom view being a mirror image of the top plan view;

FIG. 6 is a front perspective view of a decorative cap for a process transmitter embodying a second form of our new design;

FIG. 7 is a front elevational view thereof;

FIG. 8 is a side elevational view thereof with a transmitter to which it is attached shown in dotted lines;

FIG. 9 is a rear elevational view thereof; and,

FIG. 10 is a top plan view thereof; the side not shown being a mirror image of the side shown and the bottom view being a mirror image of the top plan view.

The broken line showing of a process transmitter is for illustrative purposes only and forms no part of the claimed design.
